METHOD OF AND APPARATUS FOR DIE-FORMING PARTS

George Albert Lyon, Allenhurst, N. J.

Application March 30, 1935, Serial No. 13,814
Renewed August 10, 1938

7 Claims. (Cl. 153—1)

This invention relates to improvements in a method of and apparatus for blanking parts, the invention being highly desirable for use in connection with the blanking of an automotive vehicle part, such as a tire cover part, a wheel disc part, a hub cap part, and the like.

In the making of ornamental wheel disc constructions or ornamental hub caps, a hub cap portion is usually formed in the shape of a raised crown embodying an undercut annular indentation or recess having a diameter at its bottom considerably less than the maximum diameter of the circumferential edge portion of the crown part. Such a grooving or channelling was provided in most cases for the ornamental appearance or in some cases for purposes of utility, such as furnishing room for the insertion of a lever to pry off a hub cap. Heretofore, it has been the custom of spinning such a formation in light metal parts, and this spinning operation is objectionably difficult and expensive. The parts themselves, such as a hub cap or an ornamental wheel disc embodying a hub cap, were initially stamped out or blanked with suitable die mechanism. The spinning operation was an extraneous one and a highly expensive one.

The present invention contemplates a method of forming an undercut indentation or recess in an ornamental wheel disc, hub cap, or similar element, wherein the spinning operation is eliminated.

Another object of this invention is the provision of apparatus including cooperative die members capable in a single movement of forming an undercut indentation in the skirt of a cup-shaped member.

A further object of this invention is to provide means for die-forming a crown portion of a disc-like element and providing an undercut indentation in the side wall of the crown portion.

Also an object of this invention is the provision of apparatus for die-forming a crown portion of a disc-like part in such a manner as to clinch the side wall of the crown portion about a member of less size than the crown portion disposed therein.

Still another object of this invention is the provision of die-forming apparatus wherein a metallic part having a skirt is capable of being forced against the sloping wall to cause said skirt to be deflected inwardly to form an indentation of less diameter than the rest of the part, the apparatus including means to limit the inward movement of the skirt to form an even indentation of proper configuration.

A still further object of the invention is to provide apparatus capable of die-forming the skirt of a hub cap part into a curvature substantially goose-neck in cross-section and which has a diameter at the bottom of the curvature less than 5 the maximum diameter of the hub cap part.

Also in accordance with the objects of this invention I provide a method for making wheel discs which includes the compression of a crown portion of a wheel disc into engagement with 10 securing means of less size than said portion for holding the wheel disc over the central hub of a vehicle wheel.

In accordance with the general features of this invention, there is provided a method of die-forming a hub cap, a wheel disc including an integral raised crown portion to simulate a hub cap, or a similar part, by compressing the hub cap or crown portion of the disc, preventing an outward movement of the skirt of this portion, 20 and deflecting the skirt portion inwardly, suitable means being preferably provided to limit the inward deflection so that a goose-neck curvature of proper size and configuration will be provided in the skirt.

Other objects and features of this invention will more fully appear from the following detailed description, taken in connection with the accompanying drawings, which illustrate relatively diagrammatically apparatus embodying 30 principles of the invention and capable of performing the method included in the invention, and in which:

Figure 1 is a fragmentary relatively diagrammatical central vertical sectional view of apparatus embodying principles of the present invention, showing the same in an initial stage of operation.

Figure 2 is a fragmentary view of the right hand portion of Figure 1, showing the apparatus 40 in a more advanced stage of operation.

Figure 3 is a view similar in character to Figures 1 and 2, showing a slightly different form of apparatus.

For purposes of illustration, the structure selected to be die-formed by the method and apparatus embodied in this invention is in the form of an ornamental wheel disc generally indicated by reference numeral 1. Such a wheel disc is suitable for disposition over the side surface of 50 a vehicle wheel and covers a goodly portion or all of the side surface of the wheel within the tire holding rim. The disc 1 illustrated is preferably of relatively light sheet metal and includes as an integral formation a central raised crown 55

portion 2 which, in the finished product, may simulate a hub cap.

The disc 1 is initially blanked by any suitable mechanism in the contour seen in Figure 1. In this form, the disc includes the central raised crown portion 2, the outer face or top of which is preferably arced in dome shape. This crown or hub cap portion 1 is of sufficient size to overlie the hollow hub of the vehicle wheel. The crown portion 2, of course, has a skirt or side wall 3 which terminates in a somewhat arcuate portion 4 which overlies that part of a wheel between the hub and the rim. The outer circumferential margin of the portion 4 is channelled as at 5 for the reception of the anchoring part of a decorative bead, cushioning element or other rim contacting part. Of course, the arcuate portion 4 and the channel 5 may be of any other desired configuration, these parts not being changed in any material degree by the operation of the present invention.

The apparatus for forming the disc 1 as illustrated diagrammatically in the drawings comprises in general a die block generally indicated by numeral 6, and a punch die generally indicated by numeral 7. By any suitable means, not shown, the die block is preferably held in fixed position, and the punch die 7 is movable relatively thereto. These respective parts may be associated with any suitable die-actuating mechanism, such as a punch press, in a well-known manner.

The die block 6 comprises a base portion 8 having an upstanding annular part 9 with the top face thereof arced, as at 10, so as to intimately receive thereagainst the inner face of the portion 4 of the disc. The upstanding part 9 also defines a center bore 11 in which is slidably disposed a die part 12. A suitable spring 13 seated in recesses 14 and 15 in the base 8 and die part 12, respectively, urges the die part 12 outwardly from the base to the limit defined by the inner wall of a recess 16 in the die part into which the end of a pin 17 projects. The pin is secured in any desirable manner in the annular part 9 of the die block.

The die part 12, while of a suitable diameter to properly fit within the bore 11, is provided with a reduced upwardly projecting portion 18, the top of which is arced as at 19 in dome-shape to intimately receive the inner face of the likewise arced crown portion 2 of the disc.

The punch die 7 includes a base member 20 having an integral projecting portion 21 arced as at 22 to intimately seat over the crown portion 2 of the disc. The base member is also provided with an integral annular depending flange 23 defining an annular recess 24 between itself and the central die part 21. In this recess an annular die holding element 25 is slidably mounted and held in position by the engagement of a plurality of pins 26 in a like number of recesses 27. The pins 26 are mounted in the flange 23 and the recesses 27 occur at like intervals in the holding die part 25. A plurality of springs 28, suitably seated in recesses in the base 20 and die part 25, normally urge this die part outwardly beyond the central die part 21. The die part 25 is provided with an arcuate undersurface, as indicated at 29, so as to seat intimately over the upper face of the portion 4 of the disc.

An important feature of the present invention is the fact that the die part 25 is provided with an outwardly inclined inner wall 30 substantially of the length of the skirt 3 of the disc 1. This

wall 30, while outwardly inclined with respect to the axis of the punch die, is preferably not straight but curved so as to be slightly convex, as seen in the drawings. When the disc, as above described, is placed between the die block 5 and punch die, the skirt 3 is outwardly inclined and formed so that the wall 30 preferably intimately fits against the skirt.

In the present instance, with reference to Figures 1 and 2, the disc member 1 is to be clinched in the skirt 3 about a holding member 31, by means of which the disc may be held upon a vehicle wheel. This holding member 31 is annular or ring-like in form and shaped in any suitable manner to engage over the hollow hub of a vehicle wheel or retaining means carried by the wheel. The holding or attaching member 31 is also provided with an inwardly arced outer surface which merges at its upper end into a relatively sharp curve 32 in turn merging into an arcuate upper flange 33 which intimately rests against the inner face of the dome top of the crown 2. The holding element 31 is of such a size as to fit over the portion 18 of the die part 12 and fit within the crown portion 2 of the disc. 25

In forming the disc into the desired shape and clinching the same around the holding member 31, this element 31 is first placed into position on the part 12 of the die block. Then, the disc 1 is seated upon the upper face of the die block. The punch die is then lowered or moved relatively to the die block, the annular part 25 first contacting the disc. This annular part 25 overlies the portion 4 of the disc, and the punch die must be further moved against the action of the springs 35 28 before the die part 21 contacts the crown 2 of the disc. The relative parts are now in the position seen in Figure 1.

It will be noted that the annular die part 25, held in position by the springs 28, securely holds 40 the portion 4 of the disc, and the convex and inclined wall 30 of this die part intimately surrounds the skirt 3 of the disc.

Obviously, therefore, upon a further movement of the punch die 7, the crown portion 2 of 45 the disc must be compressed, and in view of the position of the holding member 31 together with its upper flange 33 and the die part 12 of the die block, the dome top of the crown portion will not be changed in contour. The compression of the crown part must obviously result in a distortion 50 of the skirt 3. In view of the wall 30 of the die part 25, this skirt cannot be distorted outwardly but must deflect inwardly into intimate engagement around the holding member 31. 55

The additional movement of the punch die 7 to inwardly bend the skirt 3 is taken up or compensated for by a giving of the springs 13 and 28 without any lessening in the rigid holding of the dome top of the crown portion 2 and the annular portion 4 of the disc 1. As the punch die 7 moves downwardly, as the same is seen in the drawings, the die part 21 causes a forcing of the metal of the crown portion of the disc against the convex inclined wall 30 at the point 34 immediately opposite the bend 32 in the holding member 31. Due to the above formation of the top of the crown portion 2, the metal is forced against the sloping wall 30 at an angle and such forcing of the metal results in a tendency for the metal to roll inwardly around the bend 32 in the holding member 31. The inward movement of the metal of the skirt 3 is limited by the holding member, and since no flow of metal is permitted from the annular portion 4 of the disc, the skirt is formed 70 75

into a goose-neck curve, into clinched engagement with the holding member, thus providing an annular undercut recess or indentation 35 (Figure 2) in the skirt.

5 In Figure 3, I have shown how the disc 1 may be formed in the event it is not desired to clinch the same over a holding member. In some instances, it will be desirable to formulate the crown portion of the disc to simulate a hub cap and provide other means, perhaps upon the rear face of the portion 4 of the disc, for holding the same on a vehicle wheel. With reference now to Figure 3, it will be seen that the disc member 1 and punch die 7 are identically the same in construction as 10 previously described herein. The die block is also the same in construction with the exception that the die part 12 is not provided with a reduced projecting part 18, but is of the same diameter throughout and an arcuate upper surface 19 is 15 formed on this member to seat intimately against the under face of the crown 2 of the disc in like manner to the previously described portion 18 but over a greater area. Upon relative movement between the die block and punch die, a goose-neck curvature will be formed in the skirt 3 of 20 the disc, the outer wall of the die part 12 limiting the inward distortion of the skirt. However, with the convex inclined wall 30 preventing outward movement and guiding the forming of the skirt, 25 the proper curvature will result with the annular undercut recess or indentation 35 provided, causing the crown portion of the disc to simulate the appearance of a hub cap.

30 Complete details of the method embodied in my invention are believed sufficiently apparent from the foregoing as not to warrant further specific description herein.

It will be apparent that I have provided a new method of and apparatus for die-forming a metallic part, such as a hub cap, ornamental wheel disc or similar part, to provide an undercut formation in the part without the necessity of resort to an expensive spinning operation. The structure mentioned may be very simply and effectively provided in a single operation of die mechanism in a very expedient and economical manner.

I am aware that many changes may be made and numerous details of construction may be varied through a wide range without departing 50 from the principles of this invention, and I, therefore, do not purpose limiting the patent granted hereon otherwise than is necessitated by the prior art.

I claim as my invention:

55 1. The method of joining a crown-shaped part having a skirt to a circular member, including holding the circular member rigidly within the crown part, compressing the crown part while preventing outward deflection of the skirt thereof by a sloping wall, and holding the top of the crown part rigid to force the skirt inwardly into intimate clinching engagement with said member.

2. In apparatus for shaping a disc-like part having crown and ring portions and a wall portion connecting said crown and ring portions, cooperative die parts including a member for engaging the crown of said parts, an annular member concentric with said crown engaging member and mounted for relative axial movement with 60 respect thereto for engagement with the ring portion of said parts, said annular member having a sloping wall corresponding in shape to the wall portion of said part and arranged to initially contact the same, and a base member for engaging the opposite side of the ring portion from

said annular member, said crown engaging member and said base member being movable toward each other, whereby said side wall is collapsed into an inwardly extending annular portion.

3. In apparatus for uniting a disc-like part 5 having crown and ring portions and an intermediate connecting wall portion to another part, compression means for forming an inwardly extending annular indentation in the wall portion of said disc-like part for extension into locking 10 engagement with said other part comprising a member for engaging the crown of said part, an annular member concentric with said crown engaging member and mounted for relative axial movement with respect thereto for engaging the 15 ring portion of said disc-like part, said annular member having a wall for restraining outward collapse of the wall portion of said disc-like part, and a base member for engaging the opposite side of the ring portion of said disc-like part from 20 said annular member, said crown engaging member and said base member being movable toward each other thereby to compress said crown portion in an axial direction with respect to said ring portion, whereby an annular indentation is 25 formed in said side wall of said disc-like part extending into locking engagement with said other part.

4. In apparatus for uniting an outwardly inclined skirt of a disc-like part with an inwardly inclined part of less diameter, compression and forming means including a member for engaging the crown of said disc-like part, an annular member concentric with and nested around said crown engaging member and mounted for relative movement with respect thereto for engaging the ring portion of said disc-like part, said annular member having a sloping wall complementary with respect to said skirt and disposed to prevent outward deflection thereof, a base member for engaging the opposite side of the ring portion of said disc-like part from said annular member, said crown engaging member and said base member being movable toward each other, and a member nested within said base member and mounted for relative movement with respect thereto for supporting and holding said inwardly inclined part of less diameter within said crown portion when said crown engaging member is being compressed with respect to said base member.

5. Apparatus for shaping the skirt of a crown-like portion having a part extending laterally beyond said portion and in which the head of said crown-like portion has a shape other than flat, including a die member for supporting said part outside said crown-like portion, a second die member shaped for intimate contact over the head of said crown-like portion and mounted for relative movement with respect to said first die member, and an annular die member concentric with and nested around said second die member and mounted for relative movement with respect thereto for engaging the opposite face of said part outside said crown-like portion from that which is engaged by said first die member, 60 said annular member having an inner surface conforming with the initial shape of said skirt and arranged to initially contact the same, whereby when said first and second die members are axially compressed with respect to each other 65 an inwardly extending annular indentation is formed in said skirt.

6. In apparatus for shaping a disc-like part having crown and ring portions and a wall portion connecting said crown and ring portions, 70

- a cooperative die part including a member for engaging the crown of said part, an annular member concentric with said crown engaging member and mounted for relative movement with respect thereto for engaging the ring portion of said part, said annular member having a sloping wall corresponding in shape to the wall portion of said part and arranged to initially contact the same, a base member for engaging the opposite side of the ring portion from said annular member, said crown engaging member and said base member being movable toward each other, and a member disposed beneath said crown portion for limiting the extent of inward collapse of said wall portion upon compressive movement of said crown engaging member with respect to said base member.
7. In apparatus for shaping a disc-like part having crown and ring portions and an intermediate generally axially extending wall portion connecting said crown and ring portions, cooperative die parts including a member for engaging the crown of said disc-like part, an annular member nested around said crown engaging
- 10
15
